UNITED STATES PATENT OFFICE

140,402

DESIGN FOR A HOUSING FOR TRANSFORMERS OR THE LIKE

Wilbert W. Redsecker, Goshen, Ind., assignor to
Penn Electric Switch Co., Goshen, Ind., a corporation of Iowa

Application May 11, 1943, Serial No. 110,179

Term of patent 7 years

(Cl. D26—15)

To all whom it may concern:

Be it known that I, Wilbert W. Redsecker, a citizen of the United States and a resident of Goshen, in the county of Elkhart and State of Indiana, have invented a new, original, and ornamental Design for a Housing for Transformers or the like, of which the following is a specification, reference being had to the accompanying drawings forming a part thereof.

Figure 1 is a front elevation of a housing for transformers or the like embodying my new design;

Figure 2 is a side elevation thereof, and

Figure 3 is a fragmentary front elevation of the housing with the cover removed, the housing in this figure being symmetrical about a horizontal center line.

The dominant features of the design reside in the portions shown in full lines.

I claim:

The ornamental design for a housing for transformers or the like, substantially as shown and described.

WILBERT W. REDSECKER.
